(57) **CLAIM**

The ornamental design for a camera body, as shown and described.

DESCRIPTION

FIG. 1 is a top, front and right side elevational view of a camera body showing my new design;
FIG. 2 is a front elevational view thereof;
FIG. 3 is a rear elevational view thereof;
FIG. 4 is a top plan view thereof;
FIG. 5 is a bottom plan view thereof;
FIG. 6 is a right side elevational view thereof;
FIG. 7 is a left side elevational view thereof; and,
FIG. 8 is a top, front and right side elevational view thereof in a manner of use with a lens attached.
The broken line portion of a lens in FIG. 8 is shown to illustrate environment only and form no part of the claimed design.
